CLAIM

The ornamental design for a bra, as shown and described.

DESCRIPTION

FIG. 1 is a front perspective view of a bra;

FIG. 2 is a front view thereof;

FIG. 3 is a first side view thereof;

FIG. 4 is a rear view thereof;

FIG. 5 is a second side view thereof;

FIG. 6 is a top view thereof; and,

FIG. 7 is a bottom view thereof.

The broken lines depict stitching and do not form part of the claimed design.
